UNITED STATES PATENT OFFICE

JOHN J. WILMOTH AND AUGUST MOOS, OF LINCOLN, ILLINOIS

RAILWAY-CROSSING GATE

Application filed May 9, 1929. Serial No. 361,760.

The present invention is directed to improvements in railway crossing gates.

The primary object of the invention is to provide a device of this character so constructed that the gate bars will be automatically lowered upon the approach of a train and elevated upon passing of the train over the crossing.

Another object of the invention is to provide a device of this character which is exceedingly simple in construction, positive in operation, and one which can be installed at a minimum cost.

Another object of the invention is to provide a device of this character wherein novel forms of trip plates are employed for successive operation for lowering and raising the gate bars.

With these and other objects in view, this invention resides in the novel features of construction, formation, combination and arrangement of parts to be hereinafter more fully described, claimed and illustrated in the accompanying drawings, in which:

25 Figure 1 is a plan view of a section of track showing the device in place thereon.

Figure 2 is a side view thereof.

Figure 3 is a perspective view of one of the trip plates and connecting links and 30 levers.

Figure 4 is a sectional view on the line 4—4 of Figure 3.

Figure 5 is a sectional view on the line 5—5 of Figure 1.

35 Figure 6 is a side view of the roller supporting hanger showing the same connected with a part of a car or locomotive.

Figure 7 is a rear view of the hanger.

Figure 8 is a sectional view on the line 40 8—8 of Figure 1.

Figure 9 is a fragmentary view of a modified form of trip plate.

Figure 10 is a sectional view on the line 45 10—10 of Figure 9.

Referring to the drawings, 1 designates the rails of a section of track and upon the ties 2 are supported beams 3 and 4. These beams are spaced a predetermined distance 50 so that the gate tripping plates will be prop-

erly located for successive operation as a train approaches and leaves the crossing.

The beam 4 has mounted thereon brackets 5 having bearings 6 for rotatably supporting the shaft 7 and to which is fixed a trip plate 8, said plate being partially twisted intermediate its ends, as at 9, to provide angularly disposed webs 10 and 11. To one end of the shaft 7 is fixed a collar 12 having an arm 13 to which is pivotally connected the jointed link 14, said link being pivotally connected, as at 15, to a bar 16, said bar being adjustably connected to the bell crank lever 17 pivotally connected to the base plate 18 of the gate bar support 19 by a pin 20. The support 19 has pivotally mounted thereon a main gate bar 21 and an auxiliary gate bar 22, the former being adapted to act as a barrier at a main crossing while the latter closes a side-walk.

The bars 21 and 22 have toothed segments 23 and 24, respectively, carried by their lower ends. Pivotally supported by the support 19 is a lever 25 having a rack segment 26 upon its upper end which meshes with the segment 24, the lower end of said lever being pivotally connected to a series of links 27 which are connected to the bell crank lever 17. Obviously, upon rocking of the lever 25, the bars 21 and 22 will be raised or lowered.

The beam 3 has mounted thereon brackets 28 having bearings 29 for rotatably supporting the shaft 30, said shaft having fixed thereto a trip plate 31, said plate, like the plate 8, being partially twisted intermediate its ends to provide angularly disposed webs 32 and 33. To one end of the shaft 30 is fixed a collar 34 having an arm 35 pivotally connected to the bell crank lever 36, which is pivotally supported upon the plate 37.

A connector 38 is pivoted to the lever 36 and has one end of a cable 38 adjustably connected thereto, the other end of said cable being connected to a similar connector 39 pivotally connected to the series of links 27.

In Figure 9 of the drawings, the trip plate 40 is formed from sections 41 connected by lap joints 42, this construction being for the 100

purpose of adapting the plate to curved rails.

In order to actuate the trip plates successively, the locomotive or car is equipped with a hanger 43 carrying a roller 44. The hanger is provided with a strap 45 arranged to permit the hanger to freely swing over the plates without pressure when the train is backing but prevents swinging thereof as the train approaches the crossing in order that the trip plates will be successively actuated.

As shown in Figures 1 and 2, the plate 31 is in position to permit the roller to gradually press upon the web 32 and as the roller travels forward it rides upon the web 33, thus causing the plate to turn and, since the shaft 30 turns, the cable 38 will be pulled to actuate the lever 25 to swing the gate bars 21 and 22 downwardly to serve as a barrier, and as this occurs, the web 11 of the plate 8 is elevated. As the train approaches the plate 8 the roller engages the web 10, and upon further movement of the roller, the plate is rotated, and as the roller passes from the web 11 the shaft 7 will be actuated, thus actuating the bell crank 17 and the lever 25 to swing the gate bars upwardly. As the bars swing upwardly, the cable will be pulled to again elevate the web 33 of the plate 31, at which time the web 32 will be lowered, thus resetting the device for the next train.

What is claimed is:

1. The combination with a railway gate bar, of a pair of trip plates mounted adjacent the track, said plates comprising angularly disposed webs, shafts fixed to the webs, connections between the shafts and gate bar for raising and lowering the same when the webs are successively actuated, and means carried by a train passing over the track for actuating said webs.

2. The combination with a railway gate, of a pair of trip plates mounted adjacent the track, said plates comprising angularly disposed webs, shafts fixed to the webs, bell crank levers pivotally connected with the shafts, a cable connecting said levers, and means carried by the train passing over the track for successively swinging the webs of said plates to actuate the shafts, and thus the levers, to impart movement to the cable to raise and lower the gate.

3. The combination with a railway gate, of a pair of shafts rotatably supported adjacent the track, angularly disposed webs fixed to each shaft, a connection between one shaft and gate, a cable connecting said connection and end of the other shaft, and means carried by a train passing over the track for successively encountering the webs for rocking the same to actuate the cable to raise and lower the gate.

4. The combination with a railway gate, of a pair of trip plates mounted adjacent the

track and including angularly disposed webs, shafts fixed to the webs, means carried by the train passing over the track to engage the webs to successively rotate the same to raise and lower the gate, and means connecting the shafts of the respective plates successively changing the angular relationship of the webs.

5. The combination with a railway gate, of a pair of trip plates mounted adjacent the track and including angularly disposed webs, connections between each plate and gate, and means carried by the train passing over the track for engaging the webs to successively rotate the same to operate the connections to lower the gate when said means encounters one of the plates and to raise the gate when encountering the other plate.

6. The combination with a railway gate, of trip plates mounted adjacent the track, said plates comprising angularly disposed webs, shafts fixed to the plates, a bell crank lever pivotally connected with the shaft of each plate, operating means between one bell crank and gate, a cable connecting the bell cranks, and means carried by a train passing over the track for successively engaging the webs to successively operate the bell crank levers to first lower the gate and then raise the same.

In testimony whereof we affix our signatures.

JOHN J. WILMOTH. [L. s.]
AUGUST MOOS. [L. s.]
